Primary Examiner — Austin Murphy

(74) Attorney, Agent, or Firm — Kevin P. Crosby;
GrayRobinson, P.A.(57) **CLAIM**

The ornamental design for square shaped playing card reader, as shown and described.

DESCRIPTION

FIG. 1. is a left front perspective view of a second embodiment of the design.

FIG. 2. is a top plan view thereof.

FIG. 3. is a right side elevational view thereof.

FIG. 4. is a front elevational view thereof.

FIG. 5. is a bottom plan view thereof.

FIG. 6. is a rear elevational view thereof.

FIG. 7. is a left side elevational view of a second embodiment of the design.

FIG. 8. is a right front perspective view of a second embodiment of the design.

FIG. 9. is a left rear perspective view of a second embodiment of the design; and,

FIG. 10. is a right rear perspective view of a second embodiment of the design.

The broken lines shown in the drawings represent portions of the square shaped playing card reader that form no part of the claimed design.
